MULLING APPARATUS

Walter F. Piper, Oak Park, Ill., assignor to The
Beardsley & Piper Company, Chicago, Ill., a
corporation of Illinois

Application September 19, 1936, Serial No. 101,555

7 Claims. (Cl. 83—45)

The present invention relates generally to apparatus for mulling or mixing granular material. More particularly the invention relates to that type of mulling apparatus which is adapted to 5 mull, mix or recondition molding sand and comprises as the main parts or elements thereof (1) a frame; (2) an open top sand retaining receptacle which is mounted on and supported by the frame and embodies a substantially flat circular bottom and an outwardly bulged side wall 10 which is of substantially semicircular cross-section and is joined to and extends upwardly from the outer margin of the bottom; (3) a plurality of rotary balls which are arranged to travel 15 in a circular course over the bottom and around the side wall of the receptacle and are adapted during such travel to spin and effect the desired mulling, mixing or reconditioning of the sand on the receptacle bottom and between them and the outwardly bulged side wall; and (4) a motor and 20 speed reducing gearing for propelling the balls in the aforementioned circular course.

One object of the invention is to provide a 25 mulling apparatus of this type in which the receptacle is mounted to rotate or revolve about a vertical axis and is driven during operation of the apparatus so that the sand on the central portion of the bottom thereof is flung outwardly by centrifugal force into a position wherein it covers 30 the outer marginal portion of the bottom and the inner face of the outwardly bulged side wall and is disposed directly in the path of the mulling balls.

Another object of the invention is to provide a 35 mulling apparatus of the last mentioned type and character in which the receptacle is driven in a novel manner by the motor for propelling the balls over the bottom and around the side wall of the receptacle.

A further object of the invention is to provide 40 a mulling apparatus of the type and character under consideration which comprises scraper type plows behind the mulling balls for scraping the milled sand from the side wall of the receptacle and deflecting it inwards toward the central portion of the receptacle bottom so that it is moved 45 outwards by centrifugal force and aeration and a secondary mulling thereof are thus effected.

A still further object of the invention is to 50 provide a sand mulling apparatus which is generally of new and improved construction and not only is extremely efficient in operation but embodies certain features and advantages over the apparatus which forms the subject matter of 55 an application for United States Letters Patent

filed by me September 14, 1936, Serial No. 100,630.

Other objects of the invention and the various advantages and characteristics of the present sand mulling apparatus will be apparent from a consideration of the following detailed description. 5

The invention consists in the several novel features which are hereinafter set forth and are more particularly defined by claims at the conclusion hereof. 10

In the drawings which accompany and form a part of this specification or disclosure and in which like numerals of reference denote corresponding parts throughout the several views:

Figure 1 is a view partly in plan and partly in 15 horizontal section of a mulling apparatus embodying the invention; and

Figure 2 is a vertical longitudinal section taken on the line 2—2 of Figure 1 and showing in 20 detail the construction and character of the motor for driving the mulling balls and also the mechanism or means for revolving or driving the receptacle from the motor.

The apparatus which is shown in the drawings 25 constitutes the preferred embodiment of the invention. It is designed for use in a foundry or like establishment for mulling, mixing or reconditioning molding sand and comprises a frame 3, a sand holding or retaining receptacle 4, and a pair of mulling balls 5. 30

The frame 3 serves as the supporting medium for the receptacle 4. It is preferably formed of cast metal and consists of a bottom wall 6, a continuous side wall 7, and a top 8. The bottom wall 6 is designed to rest on the floor of the 35 foundry in which the apparatus is used and together with the continuous side wall 7 and the top 8 forms a gear compartment 9. The side wall 7, as shown in Figure 2, is formed integrally with and extends upwardly from the margin of the bottom wall 6 and embodies an integral out-turned flange 10 at its upper margin. The top 8 is similar in size and shape to the bottom wall 6. It serves as a closure for the upper portion of the gear compartment 9 and is removably secured to the out-turned flange 10 of the upper 40 margin of the side 7 by means of bolts 11. 45

The sand holding or retaining receptacle 4 is positioned over the top 8 of the frame 3 and consists of a flat bottom 12, an annular side wall 50 13, and an upstanding tubular member 14. The bottom is circular and overlies and is spaced a slight distance above the top 8 of the frame 3. The side wall 13 of the receptacle is substantially semicircular in cross-section and joins the top 55

face of the receptacle bottom 12 in a gradual curve. The cross-sectional diameter of the side wall is slightly greater than the diameter of the mulling balls 5. The upper margin of the side wall 13 of the receptacle is flared outwards and forms a funnel-shaped mouth 15 which serves to receive sand and direct it into the receptacle for mulling purposes. The tubular member 14 is centrally disposed with respect to the side wall 13 and is formed integrally with the bottom 12. The upper end of the member 14 terminates a slight distance above the mouth 15 and the central portion of the member is flared and embodies a substantially quadrantly curved outer surface 16 which joins the top face of the receptacle bottom and serves to direct the sand which is introduced into the receptacle outwardly over the receptacle bottom. The lower end of the tubular member 14 projects beneath the receptacle bottom 12. It extends into a conical depression or socket 17 in the top 8 of the frame 3 and is supported by a roller bearing 18 and a ball bearing 19 in such manner that the receptacle is revolvable about the axis thereof. The socket 17 is defined by means of a downwardly and inwardly extending cone-shaped wall 20 which is formed integrally with the frame top 8 and projects into the gear compartment 9. The roller bearing 18 consists of an inner race 21, an outer race 22, and an annular series of tapered rollers 23 between the two races. The race 21 surrounds the lower end of the tubular member 14 of the receptacle and is secured in place by means of a screw thread connection 21a. The outer race 22 surrounds the inner race and fits within an annular groove in the upper face of the cone-shaped wall 20. The races 21 and 22 and the rollers 23 are so arranged and constructed that the roller bearing 18 serves not only as a journal for the lower end of the tubular member 14 of the receptacle but also to prevent downward movement or displacement of the receptacle with respect to the frame. The ball bearing 19 is positioned beneath the roller bearing 18 and operates to prevent sidewise displacement or tilting movement of the receptacle. It surrounds the lower end of the tubular member 14 of the frame and consists of an inner race 24, an outer race 25, and an annular series of balls 26 between the two races. The inner race is in the form of a ring and is disposed in an annular groove 27 in the lower end of the tubular member 14. The outer race 25 surrounds and is spaced from the inner race and fits within an annular groove within the lower end of the cone-shaped wall 20. The balls 26 fit between the inner and outer races of the bearing 19 and coact with such races to form a journal for the lower end of the member 14. The roller bearing 18 and the ball bearing 19 constitute simple means for revolvably supporting the receptacle from and over the frame 3.

The mulling balls 5 are preferably two in number. They comprise metallic cores 28 and solid rubber coverings 29 and are mounted on the lower ends of a pair of substantially vertically extending shafts 30. The shafts, as shown in the drawings, extend through the cores 28 of the balls and have at their lower ends nuts 31 which engage the bottom portions of the cores 28 and prevent downward movement of the balls with respect to the shafts. The upper ends of the shafts are connected by roller bearings 32 to a pair of brackets 33 which, as shown in Figure 2, are pivotally connected by horizontally extending pins

34 to the outer ends of a cross-arm 35 so that they, together with the shafts and mulling balls, are free to swing radially with respect to the sand holding or retaining receptacle 4. The cross-arm 35 is fixedly connected, as hereinafter described, to the upper end of a vertically extending shaft 36 which extends through the tubular member 14 of the receptacle 4 and is driven, as hereinafter described, so as to cause the balls 5 to swing in a circular course around the outwardly bulged side wall 13 of the receptacle. The roller bearings 32 are disposed in cylindrical sockets 37 in the brackets 33 and permit the shafts 30 to rotate about their own axes. As a result of this arrangement the mulling balls are free to spin or rotate during travel around the side wall of the receptacle. The bearings consist of upper sections 32a and lower sections 32b. The upper sections 32a consist of outer races within the upper portions of the sockets 37, inner races around the upper ends of the shafts 30, and rollers between the races, and are arranged and constructed so that the shafts 30 are held against downward axial displacement with respect to the brackets 33. The lower sections 32b of the roller bearings consist of outer races within the lower portions of the sockets 37, inner races around the upper ends of the shafts 30 and roller bearings between the inner and outer races and are shaped and constructed, as shown in Figure 2, so that they prevent upward axial displacement of the shafts 30 with respect to the brackets. The upper ends of the sockets 37 are closed by means of caps 38 which are fixedly secured to the top portions of the brackets. The lower ends of the sockets are closed or protected against the ingress of sand by means of caps 39 which are bolted or otherwise secured to the bottom portions of the brackets and support collars 40. The latter, as shown in Figure 2, extend around the portions of the shafts 30 which are between the roller bearings 32 and the upper portions of the cores 28 of the mulling balls 5. The inner portions of the brackets are tubular in character and fit within forks 41 at the ends of the cross-arm 35. The pins 34 extend through and are journaled in the tubular portions of the brackets and fit within holes in the forks 41. In order to limit outward swinging movement of the shafts 30 and the mulling balls 5, lugs 42 and stop screws 43 are provided. The lugs project upwardly from the inner tubular portions of the brackets and then extend inwardly into overhanging relation with respect to the ends of the cross-arms 35. The stop screws 43 extend through the inwardly extending portions of the lugs and are adapted when brought into abutting relation with the cross-arm to limit outward swinging of the balls. Lock nuts 44 on the upper ends of the screws serve to hold the screws in their various adjusted positions. By adjusting the screws vertically with respect to the lugs 42 the extent of outward swinging of the mulling balls with respect to the side wall of the receptacle may be controlled. By employing the lugs and stop screws the mulling balls may be controlled so that during drive of the shaft 36 in connection with operation of the mulling apparatus the balls do not swing outwards sufficiently far to strike against the bulged side wall 13 of the receptacle. The shafts 30 are inclined upwardly and outwardly, as shown in Figure 2, when the apparatus is at rest, and the balls are mounted on the shafts so that they are positioned a slight distance above the receptacle 75

bottom 12. When the apparatus is operated by driving the shaft 36 and causing the cross-arm 35 together with the mulling balls to rotate around the receptacle, the mulling balls in response to centrifugal action swing outwards towards the receptacle side wall and effect a mulling action. The balls are so arranged and the brackets are so pivoted that when the balls swing outwardly into their operative or mulling position they are substantially concentrically positioned with respect to the side wall of the receptacle. Because the balls are supported by the shafts 30 they are free to rotate while they are moved in a circular course within the receptacle. As the result of rotation of the balls and swinging of the balls in a circular course within the receptacle, the sand is effectively mulled. The solid rubber coverings 29 are spherical and fit over and around the cores 28. By reason of the fact that the covers are formed of solid rubber the sand is yieldingly or elastically gripped for mulling purposes during operation of the apparatus. By reason of the fact that the shafts 30 are upwardly and outwardly inclined when the apparatus is at rest the balls, when the apparatus is set into operation, swing downwards and outwards and then upwards toward the outwardly bulged lower portion of the receptacle side wall. Because of this action the sand on the receptacle bottom 12 is urged outwards into the outwardly bulged side wall of the receptacle where it is subjected to the mulling action of the balls 10. As a result of the fact that the balls rotate or spin during travel in their circular course within the receptacle, the sand on the receptacle bottom 12 as well as the sand within the outwardly bulged side wall of the receptacle is subjected to mulling.

The upper end of the vertically extending shaft 36 is provided with a polygonal stem 45 and embodies a shoulder 46 beneath the stem. As shown in Figure 2, the stem fits within a polygonal socket 47 in the central portion of the cross-arm 35 and forms a driving connection between the shaft and the cross-arm whereby when the shaft is driven the cross-arm together with the shaft 36 and the mulling balls 5 is rotated bodily within the receptacle 4. The central portion of the cross-arm rests on the shoulder 46 and is locked in place by means of a cap 48 which overlies the central portion of the cross-arm and is clamped or urged in a downward direction by means of a bolt 49 which extends through the cap 48 and fits within an internally threaded socket in the polygonal stem 45. The upper end 55 of the shaft 36 is journaled in a roller bearing 50 and the lower end of the shaft is supported and journaled in a roller bearing 51. The bearing 50 consists of an outer race within the upper end of the upstanding tubular member 14 of the receptacle 4, an inner race around the upper end of the shaft 26, and an annular series of rollers between the two races. The races and rollers of the bearing 50 are arranged and constructed so as to hold the shaft against upward axial displacement with respect to the tubular member 14. The roller bearing 51 is constructed and arranged to hold the shaft 36 against downward axial displacement and consists of an outer race within a hub-like member 52 on the bottom wall 6 of the frame 3, an inner race around the lower end of the shaft 36 and an annular series of rollers between the two races. The hub-like member 52 is disposed in the gear compartment 9 and is formed as an integral part of the bottom wall 6 of the frame.

The shaft 36 together with the cross-arm and the mulling balls is driven by an electric motor 53 above the frame 3 and speed reducing gearing within the gear compartment 9 of the frame. The motor, as shown in the drawings, is located adjacent to the outwardly bulged side wall 13 of the receptacle 4 and is supported on a bracket 54. The latter overlies and is fixedly secured to the top 8 of the frame. The motor extends vertically and the lower end of the armature shaft 10 thereof extends through the frame top 8 and into the gear compartment 9 and is journaled in an upper bearing 55 and a lower bearing 56. These two bearings are formed as integral parts of the frame top 8 and the bottom wall 6 respectively. The speed reducing gearing comprises a pinion 57, an idler gear 58, a gear 59, a pinion 60, and a gear 61. The pinion 57 is fixedly secured to the lower end of the armature shaft of the electric motor 53 and meshes with, and serves to drive the idler gear 58. The idler gear is mounted on a vertically extending shaft 62 and meshes with and drives the gear 59. As shown in Figure 2, the shaft 62 is positioned in the gear compartment 9 and is journaled in an upper bearing 63 and a lower bearing 64 which are formed as integral parts of the frame top 8 and the bottom wall 6 respectively. The gear 59 is keyed or otherwise fixedly secured to a vertically extending shaft 65 which is journaled in or held in axial displacement by an upper roller bearing 66 and a lower bearing 67. The upper bearing is mounted in a socket in the top 8 of the frame 3 and the lower bearing is mounted in a socket in the bottom wall 6 of the frame. The pinion 60 is keyed or otherwise fixedly secured to the shaft 65 and is disposed between the gear 59 and the upper roller bearing 66. The gear 61 is fixed to the lower end of the shaft 36 and meshes with and is driven by the pinion 60 on the shaft 65. When the motor 53 is supplied with current it operates through the medium of the speed reducing gearing in the gear compartment 9 to drive the shaft 36, which in turn swings or rotates the cross-arm 35, the shafts 30 and the mulling balls 5.

In addition to the frame 3, the receptacle 4, and the mulling balls 5 the apparatus comprises a pair of scraper type plows 68. These plows are located directly behind the mulling balls 5 and serve during drive of the cross-arm 35 to scrape the mulled sand from the inner periphery or face of the outwardly bulged side wall of the receptacle and to deflect the sand inwardly toward the central portion of the receptacle bottom 12. They are mounted on the outer ends of a pair of radially extending angle iron bars 69 and comprise scraping parts 70 and deflecting parts 71. Preferably the plows are in the form of plate metal stampings. The scraping parts 70 of the plows are located adjacent to the outwardly bulged side wall of the receptacle and have the outer edges thereof shaped or curved conformably to the inner periphery of the receptacle side wall. As shown in Figure 2, the scraping parts of the plows extend from the bottom of the receptacle to the funnel shaped mouth 15 and are curved or rounded so that during operation or drive of the apparatus they scrape the mulled sand from the inner face of the receptacle side wall and direct it toward the deflecting parts 71. The latter extend inwardly and rearwardly with respect to the lower ends of the scraping parts and overlie the receptacle bottom 12. They project at approximately 45° angles 75

with respect to the angle iron bars 69 and operate to deflect the scraped mulled sand toward the central portion of the receptacle bottom. The angle iron bars 69 are attached to a cylindrical skirt 72 on the cross-arm 35 by means of brackets 73. They extend radially with respect to the skirt and are connected to the plows by means of angle brackets 74. The skirt to which the brackets 73 are attached is formed as an integral part of, and depends from, the central portion of the cross-arm 35 and surrounds the upper end of the tubular member 14 of the receptacle 4. The plows operate because of the specific shaping of the scraping and deflecting parts to roll or tumble the mulled sand inwards onto the central portion of the receptacle body and effect aeration of the sand as well as a secondary mulling action.

In order to cause the sand on the central or inner portion of the bottom 12 of the receptacle to move outwards by centrifugal force into the path of the mulling balls 5 mechanism is provided for rotating the receptacle conjointly with the cross arm 35. This mechanism is in the form of gearing between the electric motor 53 and the lower end of the tubular member 14 of the receptacle 4 and consists of a pinion 75, an idler gear 76 and a gear 77. The pinion 75 is fixed to the lower end of the armature shaft of the motor and is located above the top 8 of the frame 3. The idler gear 76 meshes with and is driven by the pinion 75 and is loosely mounted on the upper end of the shaft 62. The gear 77 is keyed or otherwise fixedly secured to the lower end of the tubular member 14 of the sand receiving receptacle and meshes with and is driven by the idler 76. It is disposed above the top 8 of the frame and is jammed or locked against the receptacle bottom 12 by the inner race 21 of the roller bearing 18. The idler gear 76, like the pinion 75 and the gear 77, is located above the frame top 8. A sheet metal guard 78 overlies the pinion 75 and the gears 76 and 77 and serves to protect the gearing against sand. This guard is supported in any suitable manner and is provided with a downwardly and outwardly extending skirt 79 for deflecting downwards and around the frame 3 any sand which drops upon it. When the motor 53 is operated the gearing between the armature shaft and the shaft 36 operates to drive the cross-arm 35 and the balls 5 in one direction and the gearing between the armature shaft and the lower end of the tubular member operates to drive the receptacle in the reverse or opposite direction. If it is desired to drive the receptacle in the same direction as the mulling balls but at a lower speed the idler gear 76 may be dispensed with and a larger gear may be substituted for the gear 77.

When it is desired to mull sand with the apparatus the sand to be mulled is shoveled or otherwise delivered into the mouth 15 of the receptacle 4. When striking the mouth the sand is deflected or directed into the central portion of the receptacle. When the electric motor 53 is started by supplying it with electric current the shaft 36 is driven through the medium of the speed reducing gearing in the gear compartment 9 and in turn drives the cross-arm 35, the shafts 30 and the mulling balls 5. During drive of the cross-arm the mulling balls move in a circular course around the inside of the receptacle and in response to centrifugal force move outwards towards the outwardly bulged side wall 13 of the receptacle and mull the sand between them

and said receptacle side wall. During drive of the balls around the receptacle the balls spin or rotate and effect not only mulling of the sand within the receptacle side wall but also the sand on the outer portion of the receptacle bottom. The mulled sand, that is the sand which is compressed against the side wall of the receptacle as the result of the action of the mulling balls, is scraped from the inner face of the receptacle side wall by the scraper parts 70 of the plows 68 and is deflected inwards onto the inner portion of the bottom 12 of the receptacle as the result of the action of the deflector parts 71 of the plows. As soon as the sand is deflected inwards onto the central portion of the receptacle bottom it is subjected to the action of centrifugal force resulting from rotation of the receptacle and is flung outwards onto the outer portion of the receptacle bottom and against the inner face of the outwardly bulged side wall 13 wherein it is disposed in the path of travel of the balls and is again subject to a mulling action. As the result of compression by the balls and also the action of the plows an effective and efficient mulling of the sand occurs. When the sand is mulled to the proper or desired extent the motor is stopped and the sand is removed in any suitable manner from the receptacle. Due to the fact that provision is made for rotating the receptacle deflectors for moving the sand outwards into the path of the mulling balls are unnecessary. Furthermore the effect of mulling is obtained without the necessity of having to drive the cross-arm and the mulling balls at an extremely high speed.

The herein described mulling apparatus is not only efficient in operation but may be manufactured at a low and reasonable cost due to simplicity of design and construction.

Although the apparatus has been described as being adapted primarily for use in a foundry in connection with mulling, mixing or reconditioning molding sand, it is to be understood that the apparatus may also be used to mull or condition materials other than sand and of either plastic or semi-plastic character. The invention is not to be understood as restricted to the details set forth since these may be modified within the scope of the appended claims, without departing from the spirit and scope of the invention.

Having thus described the invention, what I claim as new and desire to secure by Letters Patent is:

1. In a mulling apparatus of the character described, the combination of a frame, an open top receptacle for the material to be mulled mounted on the frame to revolve about a vertical axis and comprising a substantially flat circular bottom and an annular outwardly bulged side wall joined to and extending upwardly from the outer margin of the bottom, a freely rotatable mulling ball arranged to travel in a circular course around the side wall of the receptacle and adapted during such travel to spin and effect mulling of the material between it and said side wall, means for propelling the mulling ball in said circular course, a scraper type plow located behind and connected for conjoint propulsion with the ball and having a part shaped conformably to the inner face of the outwardly bulged side wall and adapted to scrape the mulled material from the latter and having another part positioned to direct the scraped material inwardly onto the receptacle bottom, and means for rotating the receptacle at such a speed that the material scraped by the plow and directed inwardly onto

the receptacle bottom is flung outwards by centrifugal force toward the side wall into the course of travel of the ball.

2. In a mulling apparatus of the character described, the combination of a frame, an open top receptacle for the material to be mulled mounted on the frame to revolve about a substantially vertical axis and comprising a substantially flat circular bottom and an annular outwardly bulged side wall of substantially semicircular cross-section joined to the outer margin of the bottom and extending outwardly and upwardly and then inwardly, a freely rotatable mulling ball arranged to travel in one direction in a circular course over the outer margin of the bottom and around the side wall and adapted during such travel to spin and effect mulling of the material between it and said side wall, means for propelling the ball in said circular course, an angularly disposed scraper type plow located behind and connected for conjoint propulsion with the ball and having a part shaped conformably to the inner face of the outwardly bulged side wall and adapted to scrape the mulled material from the latter and having another part positioned to direct the scraped material inwardly onto the receptacle bottom, and means for rotating the receptacle in the opposite direction at such speed that the scraped and inwardly directed material on the central portion of the bottom is flung outwards by centrifugal force towards the side wall into the course of travel of the ball.

3. In a mulling apparatus of the character described, the combination of a frame; an open top receptacle for the material to be mulled positioned above the frame and comprising a substantially flat circular bottom, a centrally disposed upstanding tubular member extending through the central portion of the bottom and having the lower end thereof journaled in bearings in the frame so that the receptacle is revolvable about a substantially vertical axis, and an annular side wall joined to and extending upwardly from the margin of the bottom; a freely rotatable mulling element arranged to travel in a circular course around the side wall of the receptacle and adapted during such travel to spin and effect mulling of the material between it and said side wall; means for propelling the mulling element in said circular course comprising a vertical power driven shaft extending through the tubular member of the receptacle and a cross arm fixed to rotate with, and projecting outwardly from the upper end of, the shaft and provided with element propelling means at its outer end; and means applied to said lower end of the tubular member of the receptacle for rotating the receptacle at such speed that the material on the central portion thereof is flung outwards by centrifugal force towards the side wall into a position wherein it is in the course of travel of the element.

4. In a mulling apparatus of the character described, the combination of a frame, an open top receptacle for the material to be mulled mounted on the frame to revolve about a vertical axis and comprising a substantially flat circular bottom and an annular outwardly bulged side wall joined to and extending upwardly from the outer margin of the bottom, a freely rotatable mulling ball disposed over the outer margin of the receptacle bottom adjacent to the outwardly bulged side wall and adapted to spin and effect mulling of the material between it and said side wall, a scraper type plow located behind the ball and

having a part shaped conformably to the inner face of the outwardly bulged side wall and adapted to scrape the mulled material from the latter during rotation of the receptacle and having another part positioned to direct the scraped material inwardly onto the receptacle bottom, and power driven mechanism for rotating the receptacle so as to cause the material on the central portion of the receptacle bottom to be flung outwards by centrifugal force toward the side wall for contact with the mulling ball for mulling purposes.

5. In a mulling apparatus of the character described, the combination of a revolvable open top receptacle adapted to contain the material to be mulled and comprising a substantially flat circular bottom and an annular side wall joined to and extending upwardly from the outer margin of the bottom, a freely rotatable mulling element arranged to travel in one direction in a circular course over said outer margin of the bottom and around the side wall and adapted during such travel to spin and effect mulling of the material between it and said side wall, means for propelling the ball in said circular course, an angularly disposed scraper type plow located behind and connected for conjoint propulsion with the element and having a part shaped conformably to the inner face of the side wall and adapted to scrape the mulled material from the latter and having another part positioned to direct the scraped material inwardly onto the receptacle bottom, and means for rotating the receptacle in the opposite direction at such speed that the scraped and inwardly directed material on the bottom is flung outwardly by centrifugal force against the receptacle side wall into the course of travel of the element.

6. In a mulling apparatus of the character described, the combination of a revolvable open top receptacle adapted to contain the material to be mulled and comprising a substantially flat circular bottom and an annular side wall joined to and extending upwardly from the outer margin of the bottom, a freely rotatable mulling element arranged to travel in one direction in a circular course around the side wall and adapted during such travel to spin and effect mulling of the material between it and said side wall, an electric motor, gearing driven by the motor for propelling the element in said circular course, a scraper type plow located behind and connected for conjoint propulsion with the element and having the leading part shaped conformably and positioned adjacent to the inner face of the side wall so as to scrape the mulled material from the latter and having its trailing part positioned and shaped to direct the scraped material inwardly onto the receptacle bottom, and gearing driven by said motor for rotating the receptacle in the opposite direction and at such a speed that the material on the bottom thereof is flung outwards by centrifugal force against the side wall into a position wherein it is in the course of travel of the element.

7. In a mulling apparatus of the character described, the combination of a frame; an open top receptacle for the material to be mulled positioned above the frame and comprising a substantially flat circular bottom, an upstanding tubular member extending through the central portion of the bottom and having the lower end thereof journaled in bearings in the frame so that the receptacle is revolvable about a substantially vertical axis, and an outwardly bulged

- side wall joined to and extending upwardly from the margin of the bottom; a freely rotatable mulling ball arranged to travel in one direction in a circular course around the side wall of the receptacle and adapted during such travel to spin and effect mulling of the material between it and said side wall; means for propelling the mulling ball in said circular course comprising an electric motor, a vertical shaft extending through the tubular member and gearing be-

tween the motor and the lower end of the shaft; and means for rotating the receptacle in the opposite direction and at such speed that the material on the bottom thereof is flung outwards by centrifugal force towards the side wall and into the course of travel of the ball, comprising gearing between said motor and said lower end of the tubular member. 5

WALTER F. PIPER.
